DESIGN FOR A DISPLAY STAND FOR COMBS AND THE LIKE

Vincent J. Dunn, New Rochelle, N. Y., assignor to Max Pressner, Brooklyn, N. Y.

Application November 23, 1945, Serial No. 124,011

Term of patent 7 years

(Cl. D80—5)

To all whom it may concern:

Be it known that I, Vincent J. Dunn, a citizen of the United States, residing at New Rochelle, in the county of Westchester and State of New York, have invented a new, original, and ornamental Design for a Display Stand for Combs and the like, of which the following is a specification, reference being had to the accompanying drawing, forming part thereof.

In the drawing:

Fig. 1 is a front elevational view of a display stand for combs and the like, showing my new design;

Fig. 2 is a side elevational view thereof; and
Fig. 3 is a rear elevational view.

I claim:

The ornamental design for a display stand for combs and the like, substantially as shown.

VINCENT J. DUNN.
